ABSTRACT OF THE DISCLOSURE

A bimetallic strip thermostat having a mounting of two abutments on opposite major faces of the strip and spaced longitudinally of each other. A resilient hold-down element engages the strip in registry with one of the abutments and on the opposite face thereof from that engaged by the abutment to sustain the strip with a free end remote from the abutments adapted to be displaced thermally.

SUMMARY OF THE INVENTION

This invention relates to bimetallic strip thermostats and more particularly to the mounting for such thermostats.

Heretofore it has been known to mount bimetallic strip thermostats at three locations along their length by locating a portion of a first major face of the strip at its actuating end on a member to be actuated, engaging an intermediate portion of the strip on a second major face with an abutment, and engaging a third portion of the strip spaced from the actuating portion of the first major face with an abutment. In such arrangements, some mechanical stress is imposed on the actuating end of the strip tending to deflect the strip from its unstressed condition in order to maintain it in a mechanically stable relationship in its mounting. Prebias by mechanical stressing is frequently undesirable as where the actuated member responds to light pressures and where the thermomechanical characteristics of the strip are distorted by stressing.

According to the present invention, bimetallic strip thermostat elements are mounted on a pair of abutments with a resilient hold-down element to maintain the strip against one of the abutments. In a preferred embodiment, the strip is formed with a convex face engaging an abutment between its region providing the thermostatic action and the second abutment. The second abutment engages an opposite face of the strip with a convex region. Adjustment of the strip around the intermediate abutment is afforded by adjusting the position of the second abutment in a direction normal to the face of the strip. The strip is supported as a cantilever from the two abutments by providing a spring finger extending as a cantilever from the intermediate abutment to the second abutment and terminating in a bifurcated end. Each hold-down end terminates in a foot of arcuate form having a radius of curvature greater than that of the strip region registering along the length of the strip with the abutment whereby the foot engages the face of the strip opposite and in the region of registry with the second abutment at two positions along its length. Movement of the second abutment thus is followed by the bimetallic strip to produce an opposite motion of the actuating region of the strip.

DESCRIPTION OF THE DRAWINGS

FIG. 1 is a side elevation of one form of bimetallic strip and its mounting as employed in an electrical snap action switch assembly;

FIG. 2 is a plan of the switch assembly of FIG. 1;

FIG. 3 is an end view of the switch assembly of FIG. 1 taken from the right as viewed in FIG. 1;

FIGS. 4 and 7 are fragmentary side elevations of modified bimetallic assemblies showing the hold-down;

2

FIGS. 5 and 8 are plans of FIGS. 4 and 7 respectively; and

FIGS. 6 and 9 are end views of FIGS. 4 and 7 respectively taken from the right.

DETAILED DESCRIPTION OF PREFERRED EMBODIMENT

The thermostat shown in FIG. 1 is the actuating means for an electrical switch 11 as disclosed in W. T. Watson Pat. 3,366,756 which issued Jan. 30, 1968, for "Snap Action Assembly." It comprises an insulating housing 12 having electrical terminals 13 and 14 and an actuating plunger 15 responsive to very light pressures normal to the upper face of housing 12 to transfer circuit conditions of the switch elements (not shown) within the housing. Switch 11 is mounted on a base 16 of channel form by means of rivets or other suitable post-like fasteners 17 and 18 and is electrically spaced therefrom, particularly at its terminals by the fiberboard sheet 19. Base 16 is secured to a two-legged bracket 21 having spaced feet with threaded bosses 22 for screw mounting the assembly.

Switch plunger 15 is moved toward and away from housing 12 by the actuating region 23 of a bimetallic strip 24 mounted on post 25 extending through a suitable aperture (not shown) in the strip. A head 26 on post 25 having a flat underside forms an abutment upon which the convex region 27 of the upper face of strip 24 rocks as a fulcrum for the strip. A region 28 of strip 24 spaced from actuating region 23 by fulcrum 27 engages an abutment 29 which can be a washer mounted on the reduced end of post 32 in abutting engagement with shoulder 33. The region 28 of engagement of strip 24 with abutment 29 is on the opposite major face of the strip from that which engages abutment 26 and is convex in form to provide a rolling contact.

Stability of the mounting of strip 24 is afforded by a hold-down 34 having a bifurcated end with each foot engaging the strip generally in longitudinally aligned registry along the strip with abutment 29 on the face opposite its contact with strip 24 and resiliently biased toward strip 24.

The hold-down 34 is bifurcated, as best seen in FIG. 2, to straddle and clear the protuberance projecting through strip 24 from abutment 29. It is cylindrical and has an arcuate form with an outer radius of curvature greater than the inner radius of curvature of the strip region 28. This, by virtue of the upstanding tail portion 35 of strip 24, provides two bearing points longitudinally spaced along strip 24 for hold-down 34 on each side of the strip as at 36 and 37 in FIG. 1. Hold-down 34 includes a cantilever spring 38 secured between the underside of the rivet 18 and the head 26 of post 25 to resiliently bias the foot toward abutment 29.

Strip 24 is arranged to engage the first abutment 26, that intermediate the actuating end and the second abutment 29, and the second abutment 29 with a rocking or rolling contact to enable smooth motion of the actuating end. Further, the strip is apertured to accommodate posts 25 and 31 extending from abutments 28 and 29 respectively. These apertures are of an extent to provide freedom around the posts and are of less extent than the abutments so that adequate bearing surfaces are provided for strip support.

Abutment 29 is adjustable by virtue of the threads (not shown) on post 32 within internally threaded collar or nut 39. Collar 39 is maintained against the upper face of base 16 by swedging a reduced section which passes through accommodating, registering apertures (not shown) in the base 16 and bracket 21 against the walls of those apertures. Backlash and any tendency to slip out of adjustment by rotation of post 32 in collar 39 is avoided by a helical spring 41 abutting the lower face of the base and

concentrically mounted on post 32 to provide a braking action by imposing tension on stem 32 and loading the threaded connection to collar 39. A washer 42 abuts the opposite end of spring 41 and is held on post 32 by a snap washer 43. Tubular stem 44 secured to post 32 protrudes beyond the feet of mounting bracket 21 and is cut away on one side at 45 to facilitate mounting a control knob or the like (not shown). Upon completion of the assembly of the switch, bimetal strip, hold-down, and adjustable abutment, the operating points for the switch are established. Collar 39 is provided with a permanent stop 40, an upstanding stub on its upper surface as viewed in FIGS. 1 and 3. A cooperating stop 46 is secured on post 32 to limit its range of rotation by engagement with stub 40. The position of stop 46 is established by subjecting the assembly to the temperature desired for an operating point at a limit, rotating the post 32 until bimetal strip 24 is shifted to a position to move plunger 15 to cause the desired operation of switch 11 and then spot welding stop 46 to the adjusted shaft 32 while indexed against stub 40. With proper design of the bimetal and matching to the switch 11 and range of adjustment of post 32, the thermostatic switch will offer a range of operating points dependent upon the degree of rotation of post 32.

In operation, the strip 24 flexes while offering some rolling contact with abutments 26 and 29 to move actuating region 23 upward or downward with changes in temperature. The critical position at which switch 11 is operated by such movement is reached at varying temperatures depending upon the positioning of abutment 29, as is readily understood by those skilled in the thermostat art.

Other forms of hold-downs for an assembly as shown in FIGS. 1 to 3 are shown in FIGS. 4 through 9. The two lines of tangency of the cylindrical foot 34 with the concave region 28 of strip 24 in the vicinity of abutment 29 provides stability to the strip by maintaining it in engagement with abutment 26 at region 27 and abutment 29 at region 28. Similar relationships are maintained in FIGS. 3 through 6 by engagement of the ends 51 of a spring 38' centered over the line of tangency of region 28' with abutment 29'. The pressure of the ends 51 upon the concave surface registering longitudinally of the strip 24' insures that the strip is maintained in place on movable abutment, both in the direction of motion of the abutment and laterally of the strip as permitted by the clearances in the apertures in the strip through which posts 25 and 32 extend.

A further interlocking of the hold-down with the bimetallic strip can be achieved by the embodiment of FIGS. 7 through 9 wherein like elements have the reference characters of FIG. 1 double primed. In this embodiment, the bifurcated ends 61 and 62 on cantilever spring 38" having protruding tongues 63 and 64 which fit into slots 65 and 66 in strip 24" which register longitudinally thereof with the region 28" engaging abutment 29. In this arrangement, the tongues 63 and 64 augment the mechanical connection offered by the down turned portion of ends 62 and 63 which engage the concave surface registering longitudinally of strip 24" with the region engaging abutment 29". In each type of hold-down balance around the second abutment transverse of the strip is assured since the transverse spacing of the areas of engagement of the ends is equally spaced around the centerline of the assembly.

It is to be appreciated that the hold-down can be mounted other than on the rivet supporting the intermediate abutment, that the intermediate abutment can be made adjustable and that reversals of functions can be made wherein the abutment for the distal end of the bimetallic strip is fixed and the intermediate abutment adjustable. In the latter arrangement, the hold-down can impose force

on the intermediate abutment. In view of the many variants and modifications in the structure which are possible, it should be recognized that the above disclosure is illustrative of the invention and is not to be read in a limiting sense.

What is claimed is:

1. A bimetallic strip having a first and second major face; a first convex region transverse of the length of said strip and extending from said second major face; a second convex region transverse of the length of said strip and extending from said first major face; a first generally planar abutment engaging said first convex region; a second generally planar abutment engaging said second convex region; said first and second abutments cooperating with said respective engaging convex regions to provide a low friction floating support for said strip, whereby said convex regions have a rolling motion upon their respective abutments when said strip is moved relative to said abutments in response to said thermal changes imposed on said strip; a base carrying said first and second planar abutments; an element secured to said base for actuation by said strip; an actuating portion on the first face of said strip spaced from said first and second convex regions and positioned to displace said element in response to thermal changes imposed on said strip; and a resilient hold-down supported in fixed relationship to said base, a strip engaging portion of said hold-down located in registry with one of said convex regions and engaging said strip on the face opposite said abutment engaged by said one convex region to bias said strip toward said abutment, and all portions of said hold-down other than said strip engaging portion being spaced from said strip.
2. A combination according to claim 1 including means to adjust one of said abutments in a direction normal to the major face of said strip engaged thereby.
3. A combination according to claim 2 wherein said adjusting means is for said second abutment.
4. A combination according to claim 1 wherein said hold-down is a cantilever spring.
5. A combination according to claim 1 wherein said hold-down is secured to one of said abutments and extends to the region in registry with the other of said abutments.
6. A combination according to claim 1 wherein each of said regions have a concave cylindrical surface on the major face of said strip opposite said convex cylindrical surface, said hold-down includes a convex cylindrical portion registering with one of said concave cylindrical regions and having a radius of curvature greater than said concave region whereby said hold-down engages said concave region along two spaced lines of contact transverse to the length of said strip.
7. A combination according to claim 1 wherein said strip has first and second apertures registering respectively with said first and second abutments and of lesser extent than said abutments, a first protuberance extending from said first abutment and having a cross-sectional area less than said first aperture, and a second protuberance extending from said second abutment and having a cross-sectional area less than said second aperture.
